UNITED STATES PATENT OFFICE.

HERAND K. NAJARIAN, OF SALT LAKE CITY, UTAH.

SCREENING MACHINE AND METHOD.

Application filed November 22, 1920. Serial No. 425,591.

To all whom it may concern:

Be it known that I, HERAND K. NAJARIAN, a citizen of the United States, residing at Salt Lake City, county of Salt Lake, 5 and State of Utah, have invented certain new and useful Improvements in Screening Machines and Methods; and I do declare the following to be a full, clear, and exact description of the invention, such as 10 will enable others skilled in the art to which it appertains to make and use the same, reference being had to the accompanying drawings, and to the characters of reference marked thereon, which form a 15 part of this specification.

The object of my invention is to produce a screening machine that will be low in first cost, will have large capacity, and will not have any vibrating or reciprocating or 20 shaking screen cloth or frame liable to rapid wear and tear.

My invention, as hereinafter described, relates to a screening machine in which the material to be screened is made to travel 25 over an inclined screen-cloth mounted on a rigid framework, and in which, during the travel of the said material over the screen-cloth, a series of impulses are imparted in rapid succession to the said material 30 through the screen-cloth and the supporting frame, said screen-cloth and the supporting frame themselves remaining substantially stationary, but serving the purpose of a medium through which the impulse 35 of a blow struck beneath the supporting frame by a hammer, is transmitted to the said material passing over the screen-cloth.

The impulse thus imparted to the material to be screened, lifts the said material off the surface of the screen-cloth, the trajectory, or the path of its travel, in the air, depending on the intensity of the impulse and the velocity of travel of the material 40 over the screen-cloth. As, of two particles of same specific gravity but of different size thrown into the air as above described, the larger particle will have the longer trajectory, when the two particles fall back to 45 the surface of the screen-cloth, the finer particles will fall back to a point closer to the point from which they were originally thrown off the surface of the screen-cloth. 50 In this way a separation of the fine particles from the coarse particles is effected in

the air, the fine particles falling on to the surface of the screen-cloth at a different position from the coarse particles. The fine particles smaller in size than the apertures in the screen-cloth pass through the said 60 apertures and drop into the undersize hopper; the coarser particles after receiving a series of similar impulses and traveling over the screen-cloth with a series of "jumps", finally go over the end of the 65 screen-cloth and fall into the oversize hopper.

The screening machines in common use at the present time that are used for fine screening, in order to obtain the necessary 70 movement and the separation of the material over the screen, make use of various shaking or vibrating devices which vibrate or shake the screen or the frame in different ways, as for instance rotate the screen 75 and the frame together in a circular path or vibrate it in its own plane or in a plane perpendicular to it. These rapid vibrations and movements on the screen-cloth and the frame on which the screen-cloth is 80 mounted, cause rapid deterioration of the moving parts, due to wear or fatigue induced in the material of construction, thus necessitating frequent repairs and renewals.

In my screening machine, a screen-cloth 85 and the framework carrying same are substantially stationary during the operation of the machine. The only moving parts in the entire machine being confined to the hammer mechanism, as hereinafter described.

My screen is particularly adapted for screening and sizing of fine ores, salt, gravel, sand, fireclay, slack coal, powdered coal, chemicals in various crystalline and 95 powdered forms, and the like.

The principle of operation of my screen may be easily illustrated with a number of billiard balls set in a row. When a blow is struck upon the ball at one end of the 100 row, the impulse of the blow is transmitted through the intermediate balls to the last ball in the row, which last ball will be thrown forward with a velocity depending on the intensity of the blow. The intermediate balls remain perfectly stationary, serving only to transmit the impulse of the blow to the last ball. Thus, in my screen, a blow struck at the bottom of a trans- 105 mitter frame is transmitted through the 110

body of the said frame and through the screen-cloth secured thereon, to the bed of material to be screened passing over the screen-cloth, lifting the said bed of material 5 away from the surface of the screen-cloth. During this operation, the screen-cloth and the frame carrying same remain stationary, just as in the case of the intermediate billiard balls mentioned above as in illustration 10 of the principle of my screening machine.

Referring to the accompanying drawings for a more complete explanation of my screening machine:

Fig. 1 is a vertical cross section of small 15 type screening machine taken on line 1—1 of Fig. 3 in the direction of the arrows;

Fig. 2 is a cross section taken on line 2—2 of Fig. 1 showing end view of dust sealing device in the undersize hopper;

20 Fig. 3 is a front view of my screening machine viewed on line 3—3 of Fig. 1 in the direction of the arrows;

Fig. 4 is a cross section of part of screen-cloth and of the transmitter frame showing 25 arched screen-cloth and step-like mounting of the screen-cloth on the transmitter frame;

Fig. 5 is a cross section of my large type machine taken on line 5—5 of Fig. 6 in the 30 direction of the arrows;

Fig. 6 is a front elevation of same taken on line 6—6 of Fig. 5 in the direction of the arrows;

Fig. 7 is an end elevation of same taken 35 on line 7—7 of Fig. 6 in the direction of the arrows; and

Fig. 8 is a section of my screening machine showing centrifugal hammer mechanism driven by a direct connected motor.

40 The screening machine is preferably made in two slightly different types, both of which however operate on the same principle. As above indicated, Figures 1, 2 and 3 show a small size of screen, while Figures 45 5, 6, and 7 cover a larger size having greater capacity.

In Figures 1, 2 and 3 the screen carrying mechanism comprises a transmitter frame which consists of a pair of spaced vertically 50 disposed plates 1, the lower ends of which are mounted upon the free end of a spring-steel plate 2, the outer end of said plate being mounted in a slot in a base casting 3. An anvil block 4 is mounted on the 55 under side of the spring plate 2 and is secured to said plate 2 and said transmitter plates 1 by means of rivets 5, the mounting of the opposite end of spring plate 2 being retained by means of rivets 6. The screen- 60 carrying edge of each plate 1 is stepped, as shown, and to the shorter sides of said steps a plurality of intermediate bars 7 and side bars 8 extend transversely of said transmitter plates 1. The screen-cloth 10 is 65 secured to the bars 7 and 8 by means of

cross slats 11 clamped to the bars 7 and 8 by bolts 12. The undersize material which passes through the screen 10 falls upon boards 13, which constitute a hopper bottom and are arranged on both sides of the 70 transmitter plates 1, as shown. For the purpose of sealing the joints between the plates 1 and the hopper bottoms 13, flanged members 14 are secured to the sides of the plates 1, as by rivets 15, and flanges 16 75 which are secured to the under sides of the boards 13 extend upward between the edges thereof and the plates 1 into the pockets provided between the members 14 and said plates 1. At each end of the hopper end boards 17 are secured to the hopper bottom 13 to retain the screened material in the hopper. The hopper bottom 13 is supported upon standards 18 and dividing walls are arranged forward of these supports to provide a chute 19 for receiving the undersize which passes through the screen and slides down from the hopper bottom 13, and a chute 20 for receiving the oversize discharged from the screen 10. The base casting 3 is secured by means of embedded bolts 21 to a concrete base 22 which also carries said supports 18.

For the purpose of operating the transmission frame 1, means is provided to engage the anvil block 4, which may be a pneumatic, steam, or mechanical hammer, as indicated at 23. This hammer has the usual set 24 which directly engages the block 4, and steam or air or the like is carried to 95 the hammer 23 by a conductor 25. The base of the hammer is provided with a plurality of jack screws 26 for the purpose of elevating the hammer to cause the set to engage the block 4 to support the weight 100 of the frame 1 and screen 10 and take said weight from the spring plate 2. In this manner a blow transmitted by the piston (not shown) in the hammer to the set 24, is in turn transmitted to the frame 21 and 105 the screen 10 in the manner above specified without imparting bodily movement to said frame and screen. Thus, as the material is fed from the feeding chute 27 to the screen 10, the undersize is caused to pass through 110 the screen and the oversize to be thrown forwardly therealong to separate the two, as above described.

The screen 10 may be mounted in several 115 different ways, as shown in the drawings. It may be stepped as by arranging it in several sections at different elevations, as shown in Figures 1 and 4. It may be stepped and slightly arched, as shown in Figure 4, or it may be arched without stepping, as indicated in Figure 5.

In Figures 5, 6 and 7, the large size screen is shown. In this form, angle bars 28 are secured to the plates 1 for supporting the screen. A cross beam 29 has its upper end 130

rolled or enlarged, as indicated, and engages the plates 1 by passing through slots therein, the edges of which slots are re-enforced by means of curved or U-shaped angle plates 41, 5 the web of the beam being spaced and maintained in spaced relation from the edges of the slots by means of spacing blocks 40. Bolts are passed through the web of the beam 29, the blocks 40 and the angle plates 10 41 to maintain the connection.

At each end of the beam 29 a guide holder 30 is secured to the under side thereof and guide rods 31 are mounted therein and held by set screws 39. Said guide rods 31 extend 15 downward into sockets in a base casting 32, supported upon the ends of cross channel-beams 33. Springs 35 are mounted between the ends of the guide holder 30 and the ends of the base casting 32 at each end of the 20 beam 29, the guide rods 31 passing through said springs 35. These springs are provided to receive the weight of the frame 1 and the screen 10 through the medium of the cross beam 29. At the center of the cross beam 29 25 the anvil block 4 is secured to the under side thereof and is adapted to be engaged by the set 24 of the hammer 23, as in the other form. The beam 29 and the hammer parts are enclosed by means of a dust shield 34, 30 which is placed over said beam and engages the same, and the shield 34 is retained by means of the bolts which connect the beam 29, the blocks 40 and the angle irons 41, above described. For the purpose of taking 35 the weight of the beam 29 and frame 1 off of the hammer, screw jacks 42 controlled by hand wheels are mounted in the castings 32 and have their upper ends in engagement with the guide holders 30. However, when 40 desired to operate the machine, the screw jacks are withdrawn to allow the weight of the parts to rest upon the hammer set 24 and the springs 35. Bolts 43 are provided to secure the channel beams 33 to supporting members 122.

The screen 10 is carried upon a framework 36, which comprises a plurality of cross members secured to the angle irons 28 on the plates 1, the screen 10 being arched 50 and fixed upon the upper ends of said cross members of the frame 36 by means of bolts 12. The under size, which passes through the screen, falls between the plates 1 into the hopper 119 directly below the screening 55 mechanism. The over size is thrown off of the screen and falls into the chute 20.

Figure 8 shows the application of a centrifugal hammer. An unbalance pulley 47 is rigidly fastened to a shaft 48 mounted in 60 a bearing 46, which is in turn attached to the under side at one end of the spring plate 45. To the upper side of the spring plate and directly above the point of attachment of the bearing casting a striking button 44 is attached. The other end

of the spring steel plate is set and fastened in a groove in a base casting 51, supported by external supports 122, and fastened thereto by bolts 52. The shaft 48 is directly connected to the shaft of an electric motor 70 50 by flexible coupling 49. The hammer mechanism is so located that the anvil block 4, under the transmitter frame 1 (Fig. 1) or the cross beam (Fig. 5) comes within close proximity of the striking button 44. 75 When the shaft 48 is rotated rapidly, the unbalanced pulley through centrifugal force created within the pulley causes the spring steel plate 45 to reciprocate in a plane perpendicular to the plane of the spring steel 80 plate, causing the button 44 to hammer the anvil block 4 once for each revolution of the unbalanced pulley 47.

The operation of my screen may be briefly described as follows:

In the small type of screen shown in Figures 1, 2 and 3, the hammer 23 is lifted up by screw jacks 26 until the weight of the transmitter frame, and the screen mounted on it, comes completely on the set of the 90 hammer. The spring steel plate 2 serves only to hold the frame in place, in balance, during the operation of the machine, and to support the frame when the hammer is taken away from the machine. The piston 95 in the hammer, not shown in the drawing, strikes the set of the hammer from below within the hammer, the impulse of the blow being transmitted to the transmitter frame and to the screen, successively, and thence 100 to the bed of material to be screened passing over the screen-cloth. The material to be screened is fed on to the screen from chute 27, the oversize going to the oversize hopper 20 and the undersize passing through 105 the screen and dropping into the undersize hopper 19.

In the large type of screening machine, as shown in Figures 5, 6 and 7, when the machine is not operating, the frame 1 is 110 lifted from the top of the hammer by screw jacks 42 controlled by hand wheels. When operating, the frame is lowered so that the weight of the frame and the screen comes on top of the set of the hammer. The 115 operation of this type of machine is substantially the same as that of the small size of machine.

I claim:

1. A screening machine comprising a 120 relatively stationary frame, a screen thereon, and a hammer having a set to receive the weight of the frame and screen, whereby the impulse of a blow of the hammer on the set will be transmitted through the set, 125 frame and screen upward to material on the screen without movement of the frame and screen.

2. A screen machine comprising a pair of vertically disposed frame members, a screen 130

- carried by said members, a block on the members at their lower portions, and a hammer engaging the block and supporting the weight of the block, members and screen, 5 whereby a blow of the hammer will have its impulse transmitted through the block, members and screen to material on the screen without movement thereof.
3. In a screening machine in which the 10 material is passed over an inclined screen of upwardly curved arch formed profile which is unyielding and undeflectable under the weight of said material means for applying force to said material from beneath 15 through the said screen cloth periodically without causing said screen to move or vibrate and with a uniform rate of concentration throughout the extent of said screen, said force lifting the bed of material away 20 from the surface of the screen and by virtue of the difference in the trajectory of the different sized particles thus thrown in the air producing separation of the coarser particles from the finer particles, the coarser 25 particles tending to segregate as a layer of uniform thickness farther away from the surface of the screen and the finer particles tending to segregate as a layer of uniform thickness nearer to the surface of the screen 30 cloth, thus enhancing the passage of fine particles smaller than the opening in the screen through the openings without being obstructed by coarser particles falling back to the surface of the screen.
- 35 4. A screening machine comprising a rigid
- frame, a screen mounted on the frame in the form of arches and so proportioned as to be unyielding and undeflectable under the weight of material to be screened passing over the screen, a plurality of vertically disposed members attached to said frame, a block on the members at their lower portions, a mechanical hammer having a set normally engaging said block and carrying the weight of said screen, frame, members and 40 block, whereby the impulse of a blow of the said hammer on the set will be transmitted through the set, the members, the frame and the screen without movement thereof. 45
5. A screening machine comprising a rigid frame, a screen mounted on the frame, a plurality of vertically disposed members attached to said frame, a block on the members at their lower portions, a mechanical hammer having a set normally engaging said block and carrying the weight of said screen, frame, members and block, whereby the impulse of a blow of the said hammer on the set will be transmitted through the 50 set, the members, the frame and the screen without movement thereof, the set of the hammer normally engaging the block on the members and adjustable means for disengaging said hammer from said block 55 causing said block, members, frame and screen to be supported by external means.

In testimony whereof I affix my signature.

HERAND K. NAJARIAN
